Copy Schedule

referred to in these Letters patent and making part
of the same containing a description in the words of the said John Stodder himself of his
Invention, which consists of the piece of the same which is
denominated the horse tooth or tongue.

Description of the Machinery used and requisite for casting the
and delivering the same, consist of a frame seven feet in width by four feet high
and twenty six inches wide the perpendicular pieces of the same being made
in two pieces and running into timbers laying horizontal and fastened to a strong
key. in this frame are placed four nuts or cylinders turned very true sixteen inches
in diameter, twenty seven inches in length except one, which is one and a half inches, including
the head at the top, five inches of each end of the nut is turned down to a diameter of
thirteen inches, the long nut to twelve in the necks these are bound with iron to prevent
swelling on the timber, and cast blocks are then placed against the upper ends of the nuts
five inches in length are turned down to fifteen inches diameter, to receive the top, and
placed in iron bands to secure the nuts from cracking, with the horizontal and
vertical pieces of the frame are secured by stone iron screws or a screw passing through
the frame, when the stone iron screws in the frame, two circular rods are placed perpendicular
through the upper and lower horizontal rods, to hold the lower piece in supporting the
weight of the nuts, crank or screw stone iron screws or iron rods are requisite to hold
the nuts. There are also two circular blocks one and a half inches in such a size as to
convenience than the nuts, one is placed before the second nut, and the other before the
first, driving them into the neck the other is placed on the opposite side before the third nut
driven forward in into the neck of a strong iron, it is secured and ready for
the press. The press consists of two iron frames seven feet wide about the same height
these frames are placed perpendicular about five feet apart, the upper pieces are
about three feet six inches in height and about seven feet in length, seven iron
bands are fastened where each has small notches to receive a lower iron band
to have the screws in the place strong iron bands are fastened to your screws are brought
equally, their parts are rendered work in the stated order fixed in the top
with each part and three out the remaining were
and set in place
through the nuts, and contains a much larger portion of the machinery principle than
the rest of the frame, which is a simple combination and utilization.
